UNITED STATES PATENT OFFICE.

ALBERT Z. SEROR, OF CHICAGO, ILLINOIS, ASSIGNOR OF ONE-HALF TO EDWARD J. HOYER.

FAN.

1,407,488.

Specification of Letters Patent. Patented Feb. 21, 1922.

Application filed March 27, 1918. Serial No. 224,945.

To all whom it may concern:

Be it known that I, ALBERT Z. SEROR, a citizen of the United States, and resident of Chicago, in the county of Cook and State 5 of Illinois, have invented a new and useful Fan, of which the following is a specification.

This invention relates to fans.

The object of the invention is to provide 10 a gear-driven, hand-operated, rotary fan of simple and relatively cheap construction and of such small size that it may conveniently be carried in a vest or other pocket. Specifically, my present invention is designed to 15 simplify, improve and cheapen the fan which forms the subject-matter of U. S. Letters Patent No. 1,243,637, dated October 16, 1917, issued to myself and Edward J. Hoyer, as joint inventors.

20 To effect these objects, a fan of my invention comprises the various features, combinations of features and details of construction hereinafter described and claimed.

In the accompanying drawing, in which 25 my invention is fully illustrated,

Figure 1 is a front view of a fan of my invention, showing the casing in section, to expose the fan operating mechanism, and the actuating plunger in extended position.

30 Figure 2 is a side view of my improved fan, also showing the casing in section, but the actuating plunger being shown at the inner limit of its movement and the parts being shown in "nested" position in dotted lines.

Figures 3 and 4 are fragmentary, sectional views on the lines 3-3 and 4-4 of Figs. 1 and 2, respectively.

Figure 5 is a detached top plan view of 40 the nut for rotating the screw and of the plunger rods for actuating the same; and

Figure 6 is a bottom plan view of said nut showing the plunger rods in section.

Referring now to the drawing, 1 designates the fan proper, 2 the fan shaft to which the fan 1 is secured, and 3 is the casing which encloses the gearing for driving said fan and which affords means for holding and operating the fan without interfering with the operative parts thereof.

As regards its usual features, and, excepting as hereinafter particularly pointed out, the fan proper 1 is of a usual type and will be readily understood from the

drawing without a detailed description 55 thereof.

To provide for turning the vanes or blades of said fan into extended position, as shown in Fig. 1, and into folded or nested position, as indicated in dotted lines 60 in Fig. 2, said vanes or blades are mounted on a bushing 4 so as to turn thereon relatively to each other. In practice, one of said vanes, as the outer vane 1', is preferably secured to said bushing 4 so as to turn therewith. Convenient means for thus securing said fan vane 1' to the bushing 4 so as to rotate therewith, consists in expanding said bushing into strong frictional engagement with the hole in said fan vane through which 70 said bushing extends. My invention, however, contemplates any other desired or approved means for thus securing said vane or blade 1' to said bushing, as by soldering said fan vane or blade to said bushing. 75 The inner vane or blade 1² is free to turn on the bushing 4, thus providing for desired relative pivotal movement of said fan vanes or blades.

To provide for securing said fan vanes or blades in folded and extended positions, said vanes or blades are provided at their attached ends with interlocking beads and grooves 5 and 6 formed by struck-up portions of said vanes or blades arranged symmetrically at opposite sides of the pivotal axes thereof. As shown, said beads and grooves are formed by striking or stamping up substantially similar beads on said vanes or blades, the ribs on one thereof forming 90 grooves adapted to receive and interlock with the ribs on the other.

In operation, the beads 5 are formed on the inner vane or blade 1² and the grooves which receive said blades on the outer vane 95 or blade 1', said beads and grooves being held yieldingly in engagement when in folded and extended positions by means of a spring 7 inserted between the pivoted end of the inner vane or blade 1² and a flange 100 8 formed at the inner end of the bushing 4, said spring being preferably wound helically so that it will engage the attached end of the inner fan vane or blade 1² at an appreciable distance from the bushing 4.

105 My invention contemplates attaching the bushing 4 to the fan shaft 2 in any desired manner so that the fan proper 1 will rotate

with said shaft. Simple means for this purpose consists in slightly tapering the outer end of the fan shaft 1 and in correspondingly tapering the hole through the bushing 4, whereby said bushing may be forced onto said fan shaft and into strong frictional engagement therewith.

The casing 3 forms the frame of the fan on which the operative parts thereof are 10 mounted and by which the fan is held while being operated.

In the preferable construction shown, said casing consists of a barrel 9, made of any suitable material, as rubber, papier mâché, or 15 the like, secured to the ends of which are caps 10 and 11, preferably made of suitable sheet metal, being conveniently stamped from thin sheet steel.

The fan shaft 2 is preferably mounted so 20 as to rotate freely in bearings formed in the cap 10 secured to what, for purposes of convenient reference, will be called the upper end of the casing 3, the relation being such that the axis of the fan shaft will extend 25 substantially at right angles to the axis or center line of said casing.

The gearing for driving the fan 1 consists of a screw 12 the ends of which are 30 cut down to form journals which engage suitable bearings formed in the lower cap 11 and in a bearing member 13 supported within the fan casing at a short distance below the fan shaft 2. As shown, said bearing member consists of an end wall of the 35 barrel 9, but my invention contemplates any desired or approved form of bearing member. For reasons presently explained, the screw 12 is shorter than the distance between its bearings in the cap 11 and the bearing member 13, thus providing for 40 limited endwise movement of said screw.

The journal on said screw which has its bearing in the bearing member 13 is made of sufficient length so that it will project 45 through said bearing member and secured to the end thereof above said bearing member, is a gear 14 the teeth of which are adapted to engage the teeth of a gear 15 secured to rotate with the fan shaft 2.

50 While my invention contemplates the use of any desired or approved form of gear wheels 14 and 15, I prefer, on account of the cheapness with which they can be manufactured, to use spur gears stamped from 55 suitable sheet metal, in the manner that lock gears are largely made, the teeth of the gear 14 being bent upwardly at an angle of approximately 30 degrees to a plane at right angles to the axis of the screw 12, 60 so that the ends of the teeth of said gear 14 will intermesh with the teeth of the gear 15.

The screw 12 is made sufficiently shorter than the distance between its bearings to 65 permit endwise movement thereof to effect

engagement and disengagement of the teeth of the gear 14 secured to said screw with the teeth of the gear 15.

Rotation is adapted to be imparted to the screw 12 in opposite directions by reciprocating movement of a nut 16 threaded to said screw, said nut being held against rotation during such reciprocating movement.

Said nut is adapted to be maintained normally, yieldingly at the outer limit of its 70 movement by a coiled spring 17 inserted between the bearing member 13 and the nut 16 and preferably permanently connected to said nut, the extreme outer position of the nut being defined by contact thereof with the cap 11 secured to the outer end of the barrel 9.

Movement is adapted to be imparted to the nut 16 against the force of the spring 17 by means of a plunger connected thereto 85 and which is longitudinally movable in a suitable bearing formed in the cap 11 secured to the outer end of the tube or cylinder 9, said plunger and the bearings therefor in the cap 11 being so constructed and ar-

ranged that they will not interfere with the screw 12 or the bearings therefor in said cap 11. As shown, said plunger preferably consists of spaced rods 18 fitted to and freely movable endwise in suitable bearings formed 90 in the cap 11 at opposite sides of the bearing for the journal of the screw 12, the inner ends of said rods being rigidly secured to the nut 16 and their outer ends being rigidly connected to a button or pressure plate 19. Said rods will thus hold the nut against rotation, in the manner desired.

The nut 16 is preferably made in the form of what may be described as a thimble having straight sides and which is slightly 100 smaller than the inside diameter of the barrel 9, in which form it may be stamped, at slight cost, from suitable sheet metal. Formed in the end of said nut is a hole or opening 20, the shape of which conforms 105 to the shape in cross-section of the screw 12 and which is sufficiently larger than said screw to permit the same to pass freely therethrough, while, at the same time, imparting rotary movement to said screw in 110 opposite directions as the nut 16 moves in or out. As shown, the screw 12 has a double thread, which will make its shape in cross-section symmetrical at opposite sides of its axis. I do not, however, desire to 115 limit myself to a screw having a double thread nor to a nut of the specific construction shown.

To provide for conveniently and securely attaching the rods 18 to the nut 16, said 120 nut is preferably provided at opposite sides with grooves 21 adapted to receive the inner ends of said rods, which are secured therein in any desired manner, as by means of solder.

To provide for conveniently holding and operating the fan so as not to interfere with the rotation of the fan 1, the fan casing is provided, on the side thereof opposite to 5 said fan proper, with a finger grip 22. In use, the fan is designed to be held between the thumb applied to the pressure plate 19, and a finger or two of the same hand applied to the finger grip 22, said finger grip 10 affording a purchase for applying force to said plunger by means of the thumb, in an obvious manner.

To provide for folding the finger grip 22 against the side of the fan casing, said 15 finger grip is preferably hinged or pivoted to said casing, its movement under the stress to which it will be subjected in use, being limited by a suitable stop. Preferably, also, said finger grip is so constructed and ar- 20 ranged that it may be engaged with the nut 16, when said nut is at or adjacent to the inner limit of its movement under the influence of pressure applied to the plunger 18, the relation being such that the pressure 25 of the spring 17 on said nut will operate to hold said finger grip turned into position against the side of the casing 3 and said finger grip operating to lock said nut and the plunger 18 substantially at the limit of 30 their inward movement, in which positions of said finger grip and of said plunger, said fan casing and associated parts will occupy the least possible space.

In the specific construction shown, the 35 finger grip 22 is pivoted to the inner side of a plate 23 rigidly secured to the cap 10 and its free end projects outwardly through a slot 25 in said plate. Pivotal movement of said finger grip to define its operative 40 position is limited by contact thereof with the lower end of the slot 25.

The nut 16 and the plunger rods 18 are adapted to be secured at the inner limit of their movement by a lip 24 formed on the 45 finger grip 22 preferably at a point beyond its pivot, the relation being such that when said finger grip is turned against the side of the casing into inoperative position, said lip 24 will project through a slot 26 formed in 50 the barrel 9 of the fan casing, into the path of movement of the nut 16. Thus, by forcing the nut 16 inwardly beyond the lip 24 by means of the plunger applied thereto, turning said finger grip into position against 55 the side of the fan casing, and releasing the pressure on the plunger applied to said nut, said nut will be forced outwardly by the spring 17 into contact with the lip 24, which will thus lock said nut 16 and the plunger 60 applied thereto at approximately the inner limit of their movement and the finger grip in folded position, all in the manner desired.

While the means shown for pivoting said finger grip and for holding same in folded 65 and extended positions and for locking the

plunger applied to the nut 16 in "pressed-in" position, embody what I now consider to be the preferable means for this purpose, I do not desire to limit myself thereto, as other means will readily suggest themselves to 70 skilled mechanics.

In use, the fan is designed to be held between a thumb applied to the pressure plate 19 at the outer end of the plunger 18 and a finger or two of the same hand applied to 75 the finger grip 22, and pressure is alternately applied to the end of said plunger to force the same inwardly and is then relieved, whereupon the spring 17 will force the nut 16 and plunger 18 outwardly. Owing to the 80 fact that the threaded portion of the screw 12 is shorter than the distance between its bearings, the initial movement of said nut caused by pressure applied to the plunger 18, will impart bodily endwise movement to 85 said screw to effect engagement of the teeth of the gear 14, on the inner end of the journal of said screw with the teeth of the gear 15 on the fan shaft, and, after engagement of said gears is effected, further movement of 90 said nut due to pressure applied to said plunger will impart rotation to the screw 12, and through the gears 14 and 15, to the fan shaft 2 and fan 1. When movement of the nut 16 due to pressure on the plunger 18 ceases, as 95 when said plunger and nut reach the inner limits of their movement, the momentum of the fan 1 will cause the fan shaft 2 to continue to rotate and rotation of said fan shaft will operate, through the gears 14 and 15, to 100 105

impart rotation to the screw, such rotary movement of said screw through its screw threaded engagement with the nut 16, operating to impart bodily endwise movement to said screw, which will continue until the gear 14, on said screw is disengaged from the gear 15 on the fan shaft, whereupon the fan 1 will continue to rotate for a considerable time under its own momentum, while the screw 12 will come to rest and will remain at rest until the pressure on the plunger 18 is relieved and the nut 16 begins to move outwardly under the pressure of the spring 17, which will impart rotation to said screw in a reversed direction to that in which it will be turned by inward movement of said nut due to pressure on the plunger. Due to the action described, it is possible to operate the plunger 18 in what may be described as in intermittent or irregular manner—said plunger being forced inwardly to give an impulse to the fan 1 and held stationary, usually at the inner limit of its movement, for a considerable interval of time, disengagement of 110 115

said gears 14 and 15 being effected by continued rotation of said screw 12 due to the momentum of the fan. But for the action and manner of effecting disengagement of the gears 14 and 15 described, rotation of the fan would stop when the nut 16 reached the in- 120 125 130

ner limit of its movement or was held stationary at any point in its inward movement, for the reason that while the initial outward movement of the nut 16 under the influence of the spring 17 would impart bodily endwise movement to said screw outwardly and would thus effect disengagement of the gear 14, thereon from the gear 15, disengagement in this manner could not take place so long as the nut was held stationary by the plunger 18, and in any event could not take place even if the pressure on said plunger was relieved instantaneously, as a slight interval of time would necessarily elapse before the plunger and nut could be released and could respond to the pressure of the spring 17, and, during this interval, said nut and screw would be held stationary, thus preventing disengagement of the gears 14 and 15, which would stop the fan 1 abruptly.

With the described construction, it is, therefore, obvious that intermittent impulses will be imparted to the fan by pressing the plunger inwardly at intervals, the frequency of which will depend upon the rapidity with which said plunger is operated and that, at the end of each impulse, the fan 1 will continue to rotate under its own momentum regardless of the interval of time which elapses before the nut is released so as to respond to the pressure of spring 17.

I claim:—

1. In a fan, the combination of a casing, a fan shaft mounted therein, a screw, a nut threaded thereto, said screw and nut being mounted, one so as to admit of rotary and limited endwise movement and the other so as to admit of reciprocating movement, means for reciprocating the latter, and gearing connecting said rotary member and fan shaft, the relation being such that movement of said reciprocating member will rotate said rotatable member, the initial movement of said reciprocating member to rotate said rotatable member imparting endwise movement to said rotatable member to effect engagement of the gearing connecting said rotatable member with the fan shaft, and the relation being such also that rotation of said rotatable member from said fan shaft by means of said gearing will operate through the screw threaded engagement of said rotatable member with said reciprocating member to effect disengagement of said gearing, substantially as described.

2. In a fan, the combination of a casing, a fan shaft mounted therein, a screw rotatably mounted in said casing so as to admit of limited endwise movement, a nut threaded to said screw, means for imparting reciprocating movement to said nut, gearing connecting said screw and fan shaft, engagement and disengagement of which is adapted to be effected by endwise movement

of said screw, reciprocating movement of said nut operating to rotate said screw, the relation being such that the initial movement of said nut in one direction will effect engagement of the gearing connecting said screw and fan shaft and such also that rotation of said screw from said fan shaft by the connecting gearing will operate through the screw threaded engagement of said screw with said nut to effect disengagement of said gearing, substantially as described.

3. In a fan, the combination of a casing, a fan shaft mounted therein, a screw rotatably mounted in said casing so as to admit of limited endwise movement, a nut threaded to said screw, means for imparting reciprocating movement to said nut, gears on said screw and fan shaft, the relation being such that endwise movement of said screw in opposite directions will operate to effect engagement and disengagement of the gear thereon with and from the gear on said fan shaft, the relation being such that the initial movement of said nut in one direction will impart endwise movement to said screw to effect engagement of the gear on said screw with the gear on said fan shaft and such also that rotation of said screw from said fan shaft through the gears connecting said screw and fan shaft will operate through the screw threaded engagement of said screw with said nut to effect disengagement of the gear on said screw from the gear on said fan shaft, substantially as described.

4. In a fan, the combination of a casing, a fan shaft mounted in said casing, fan blades secured to said fan shaft, and means for rotating said fan shaft, said means comprising a screw rotatably mounted in bearings in said casing comprising a bearing member supported within the casing adjacent to the fan shaft, and the journal of said screw extending through and beyond its bearing in said bearing member, a nut threaded to said screw and means for imparting reciprocating movement to said nut lengthwise of said screw, a gear secured to the end of the journal of said screw adjacent to said fan shaft, and a gear on the fan shaft adapted for engagement therewith, said screw being sufficiently shorter than the distance between its bearing to permit endwise movement thereof under the pressure applied to the nut threaded thereto to effect engagement and disengagement of the gear on said screw with and from the gear on the fan shaft when endwise movement is imparted to said screw in opposite directions, substantially as described.

5. In a fan, the combination of a casing, a fan shaft mounted in said casing and which projects through a wall thereof, fan blades secured to the projecting end of said shaft, and means for rotating said fan shaft, said means comprising a screw rotatably

- mounted in bearings in said casing comprising a bearing formed in a bearing member supported within said casing adjacent to the fan shaft, and the journal of said 5 screw extending through and beyond its bearing in said bearing member, a nut threaded to said screw, means for holding said nut from rotating, and means for imparting reciprocating movement thereto 10 lengthwise of said screw, a gear secured to the end of the journal of said screw adjacent to said fan shaft, and a gear on the fan shaft adapted to engage therewith, said screw being sufficiently shorter than the distance 15 between its bearings to permit endwise movement thereof to effect engagement and disengagement of the gear on said screw with and from the gear on the fan shaft, substantially as described.
- 20 6. In a fan, the combination of a casing, a fan shaft mounted in said casing and which projects through a wall thereof, fan blades secured to the projecting end of said shaft, and means for rotating said fan shaft, said 25 means comprising a screw rotatably mounted in bearings in said casing comprising a bearing formed in a bearing member supported within said casing adjacent to the fan shaft, and the journal of said screw extending through and beyond its bearing in 30 said bearing member, a nut threaded to said screw, means for holding said nut from rotating, and means for imparting reciprocating movement thereto lengthwise of said screw, a gear secured to the end of the journal of said screw adjacent to said fan shaft, and a gear on the fan shaft adapted to engage therewith, said gears comprising a spur gear and a gear the teeth of which 35 are 40 extend at an angle to the plane in which said gear is supported, said screw being sufficiently shorter than the distance between its bearings to permit endwise movement thereof to effect engagement and disengagement of the gear thereon with and from the gear secured to the fan shaft, substantially as described.
7. In a fan, the combination of a casing, a fan shaft mounted in said casing and which projects through a wall thereof, fan blades secured to the projecting end of said shaft, and means for rotating said fan shaft, said means comprising a screw rotatably mounted in bearings in said casing comprising a bearing formed in a bearing member supported within said casing adjacent to the fan shaft, and the journal of said screw extending through and beyond its bearing in said bearing member, a nut 50 threaded to said screw, and means for imparting reciprocating movement thereto lengthwise of said screw, said means comprising spaced plunger rods the inner ends of which are secured to said nut and which 55 are positioned at opposite sides of the screw to which said nut is threaded, said plunger rods being freely movable endwise in suitable bearings formed in the fan casing and projecting outside thereof, the relation being such that pressure applied to the end of said 60 plunger rods will force said nut inwardly, and gearing connecting said screw and fan shaft constructed and arranged for imparting rotary movement to said fan shaft continuously in one direction and for disengaging said gearing through the screw threaded engagement of said nut and screw when movement of said nut to rotate said screw and fan shaft ceases, substantially as described. 70
8. In a fan, the combination of a casing, a fan shaft mounted therein and which projects through a wall thereof, fan blades secured to the projecting end of said shaft, and means for rotating said fan shaft, said 75 means comprising a screw rotatably mounted in bearings in said casing, a nut threaded to said screw, means for holding said nut from rotating, means for imparting reciprocating movement to said nut lengthwise of said screw, comprising a plunger applied to said nut, the end of which projects beyond the fan casing, the relation being such that pressure on said plunger will force said nut inwardly, a finger grip pivoted upon the fan casing affording a purchase for exerting pressure on said plunger, a stop which limits the pivotal movement of said finger grip under the stress to which it is subjected in use, and gearing connecting 85 said screw and fan shaft constructed and arranged for imparting rotary movement to said fan shaft continuously in one direction, substantially as described. 90
9. In a fan, the combination of a casing, a fan shaft mounted therein and which projects through a wall thereof, fan blades secured to the projecting end of said shaft, and means for rotating said fan shaft, said means comprising a screw rotatably mounted in bearings in said casing, a nut threaded to said screw, means for holding said nut from rotating, means for imparting reciprocating movement to said nut lengthwise of said screw, comprising a plunger applied to said nut, the end of which projects beyond the fan casing, the relation being such that pressure on said plunger will force said nut inwardly, a finger grip pivoted upon 95 said fan casing, a lip projecting from the pivoted end of said finger grip and extending at an angle thereto, the member to which said finger grip is pivoted being provided with a slot through which said lip extends, contact of said finger grip with said slotted member operating to limit the pivotal movement of said finger grip in use, and gearing connecting said screw and fan shaft constructed and arranged for imparting 100 rotary movement to said fan shaft substantially as described. 105
10. In a fan, the combination of a casing, a fan shaft mounted therein and which projects through a wall thereof, fan blades secured to the projecting end of said shaft, and means for rotating said fan shaft, said means comprising a screw rotatably mounted in bearings in said casing, a nut threaded to said screw, means for holding said nut from rotating, means for imparting reciprocating movement to said nut lengthwise of said screw, comprising a plunger applied to said nut, the end of which projects beyond the fan casing, the relation being such that pressure on said plunger will force said nut inwardly, a finger grip pivoted upon 110 said fan casing, a lip projecting from the pivoted end of said finger grip and extending at an angle thereto, the member to which said finger grip is pivoted being provided with a slot through which said lip extends, contact of said finger grip with said slotted member operating to limit the pivotal movement of said finger grip in use, and gearing connecting said screw and fan shaft constructed and arranged for imparting 115 rotary movement to said fan shaft substantially as described. 120
11. In a fan, the combination of a casing, a fan shaft mounted therein and which projects through a wall thereof, fan blades secured to the projecting end of said shaft, and means for rotating said fan shaft, said means comprising a screw rotatably mounted in bearings in said casing, a nut threaded to said screw, means for holding said nut from rotating, means for imparting reciprocating movement to said nut lengthwise of said screw, comprising a plunger applied to said nut, the end of which projects beyond the fan casing, the relation being such that pressure on said plunger will force said nut inwardly, a finger grip pivoted upon 125 said fan casing, a lip projecting from the pivoted end of said finger grip and extending at an angle thereto, the member to which said finger grip is pivoted being provided with a slot through which said lip extends, contact of said finger grip with said slotted member operating to limit the pivotal movement of said finger grip in use, and gearing connecting said screw and fan shaft constructed and arranged for imparting 130 rotary movement to said fan shaft substantially as described. 130

tinuously in one direction, substantially as described.

10. In a fan, the combination of a casing, a fan shaft mounted therein and which projects through a wall thereof, fan blades secured to the projecting end of said shaft, and means for rotating said fan shaft, said means comprising a screw rotatably mounted in bearings in said casing, a nut threaded 10 to said screw, means for holding said nut from rotating, means for imparting reciprocating movement to said nut lengthwise of said screw, comprising a plunger applied to said nut, the end of which projects beyond 15 the fan casing, the relation being such that pressure on said plunger will force said nut inwardly, a finger grip pivoted upon said fan casing, a lip projecting from the pivoted end of said finger grip and extending 20 at an angle thereto, the fan casing being provided with a slot through which the lip on said finger grip projects into said fan

casing, contact of said finger grip with a rigid part of the fan casing operating to limit the pivotal movement of said finger 25 grip in use, and the relation being such that when said finger grip is folded against the side of the fan casing, said lip will project into the path of movement of the nut threaded to the screw at a point below said nut 30 when substantially at the inner limit of its movement, and will be out of the path of movement of said nut when said finger grip is turned into extended position, and gearing connecting said screw and fan shaft 35 constructed and arranged for imparting rotary movement to said fan shaft continuously in one direction, substantially as described.

In testimony, that I claim the foregoing 40 as my invention, I affix my signature this 21st day of March, 1918.

ALBERT Z. SEROR.
